UNITED STATES PATENT OFFICE.

VINCENT RAGGNA, OF NEW YORK, N. Y., ASSIGNOR TO CARY MANUFACTURING CO., OF BROOKLYN, NEW YORK, A CORPORATION OF NEW YORK.

ART OF MAKING CORRUGATED FASTENERS.

Application filed September 29, 1921. Serial No. 504,049.

To all whom it may concern:

Be it known that I, VINCENT RAGGNA, a citizen of the United States, residing at the city of New York, borough of Brooklyn, county of Kings, and State of New York, have invented a certain new and useful Art of Making Corrugated Fasteners, of which the following is a specification.

This invention pertains to the art of making corrugated fasteners; the object being to so fabricate the metal stock as to impart the desired formation thereto without drawing the temper of said stock by heating the metal, while at the same time facilitating the necessary operations so as to produce the character of fastener desired in an economical manner.

In the art of making corrugated fasteners it is desirable to avoid grinding the metal at any stage in the fabrication of the metal for the reason that the frictional contact of the metal stock with the grinding surface results in an undesirable heating of the metal, with a consequent tendency to draw the temper of the metal to such an extent as to render it too soft, and in addition thereto, such grinding operation is relatively slow, and it sets free a certain amount of dust which is seriously objectionable in the workroom.

According to the present invention, the metal stock is treated along the resulting driving edge so as to produce reversed bevels thereon by a shaving or paring operation, the utility of which is to sharpen the driving edge without drawing the temper of the metal; and should the shaved stock be utilized subsequently in the production of saw tooth fasteners or divergent fasteners, the preliminary removal of the metal by the shaving or paring process reduces the quantity of metal required to be cut away for the production of the saw teeth on the driving edge of the fastener, whereby the production of the fasteners is facilitated and economy of manufacture is attained.

In practically carrying out the shaving operation I employ means for directing the metal stock in a path intermediate a plurality of knives, the latter being positioned at opposite sides of said path and being inclined to the line of feed so as to present the cutting edges for contact with the respective lateral faces of the stock adjacent one edge thereof. Said knives act to pare

or shave the metal from the stock with a continuous operation so that thin narrow ribbons or shavings of metal are pared off the stock and discharged out of the path of feed, whereby the stock is beveled on the opposite faces and such bevels are reversely inclined so as to converge toward each other, resulting by the conjoint action of the knives in a sharpened edge on the metal stock.

Said knives are mounted in heads which in turn are fitted for the required adjustment in rockable carriers, the latter being pivotally mounted adjacent the line of feed and positioned with accuracy by the adjustment of certain locating devices, such as set screws. The carriers are thus adapted for movement in a manner to position the knives at the angles required for shaving the metal from the stock, and the knife-carrying heads may be raised or lowered with respect to the rockable carriers in order to present the knives to the edge portion of the metal stock, such adjustment being desirable for the required action of the knives upon different widths of the metal stock.

Other functions and advantages of the invention will appear from the following description taken in connection with the accompanying drawings, wherein—

Figure 1 is a diagrammatic view illustrating the stages of operations followed in the production of corrugated saw tooth fasteners according to this invention.

Figure 2 is an enlarged view in plan of the stock shaving mechanism.

Figures 2^a and 2^b are cross sections on the lines 2^a—2^a and 2^b—2^b, respectively, of Figure 2 illustrating the metal stock prior to the shaving operation and subsequently thereto.

Figure 3 is a side elevation of the stock-shaving mechanism looking toward the right of Figure 2.

Figure 4 is a vertical cross section partly in elevation, the plane of the section being indicated by the dotted line 4—4 of Figure 2 looking in the direction of the arrow.

Figure 5 is a view partly in plan and partly in horizontal section illustrating one of the knives, the adjustable head therefor, and the rockable carrier for said head.

Figures 6, 7 and 8 are views in section partly in elevation illustrating the successive steps for the production of saw tooth fasteners from the shaved metal stock.

Figures 9, 10 and 11 are views of the dif-

ferent types of fasteners adapted to be produced from the shaved metal stock.

The metal stock A is a relatively narrow band of tempered steel of the required gage and width, indefinite as to length, and contained in a coil or reel a, see Figures 1 and 2, mounted in or adjacent a table B of the shaving mechanism.

Said table is provided with a guide channel c bounded by channel-forming members C C', which members are shown as plates positioned in parallel relation and fixedly attached to the table. The members or plates extend lengthwise of the table for directing the metal stock in a predetermined path, and they operate to retain said stock in the position required for the shaving action of the knives D E, the latter being mounted for their cutting edges to be presented at the necessary angles into contact with the metal stock on the opposite sides or faces thereof and adjacent that edge of the stock which constitutes the driving or penetrating edge of the fasteners subsequently produced.

The metal stock is fed continuously within the guide channel c by suitable means, the feed means being depicted in Figure 1 as a set of co-operating rolls F operating on said stock to impart the feed motion thereto and to corrugate the stock in a well known manner, but obviously the means for feeding the metal stock may be changed as desired.

Co-operating with the table B are stock guides f f' positioned in alignment with the channel c and operating to direct the stock to said channel as it is drawn off the reel a and to direct the stock after it passes out of the channel c, one or more directing rolls f² being positioned intermediate the second stock guide f' and the feed rolls F. As shown in Figure 2, each guide f or f' is provided with wipers f³ for contact with the metal stock for removing therefrom dust or dirt adhering to the surface of the metal.

The knives D E are positioned at opposite sides of the guide channel, and are inclined relatively thereto, whereby said knives are presented for contact with the respective sides or faces of said stock adjacent the edge thereof. The knives D E are positioned one in the rear of the other, and said knives are inclined in opposite directions one to the other, one knife D being inclined in one direction with respect to the plane of the guide channel c, whereas the other knife E is inclined in an opposite direction with reference to said plane of the guide channel, see Figure 2.

As shown more clearly in Figures 2 to 5 inclusive, each knife is an elongated blade with a cutting edge at the end adjacent the channel guide, said knife being fitted in an opening d of a head shown as a block G, whereby the knife is adapted to be held

fixedly in position by a binding screw d' so as to permit the desired adjustment of the knife by moving it in a longitudinal direction. The head block is fitted within a suitable guideway h of a rockable carrier H, one form of said guideway and the form of the head block being shown in Figure 5; the guideway operating to retain the head block from rotative movement while permitting the head block and the knife to be adjusted in a vertical direction, for which purpose a screw spindle I is employed. The screw spindle has a swiveled connection at i with the carrier H and a threaded connection with the head block, see Figure 4, said spindle extending upwardly from the carrier and being provided with a cross pin i' serving the purposes of a handle for readily turning said spindle.

There are two head blocks G, and two carriers H, one for each of the two knives D E, and these carriers are positioned upon the table B at opposite sides of the channel guide for the metal stock. Each carrier is shown as having an arm h' attached pivotally to the table by an arbor h², the latter serving as the axis of movement for the carrier so as to make provision for movement of the carrier and the head block with the knife relatively to the channel guide, as a result of which each knife may be shifted with respect to the metal stock whereby the knife acts to cut or shave the metal stock at a definite angle, whereas the adjustment of the knife longitudinally with reference to the head block regulates the depth of the cut by the knife into the metal stock. Each pivoted carrier is held fixedly in position by suitable means, shown as screws J J', one of which finds a threaded bearing in the arm h' of the carrier, whereas the other screw is supported in a post j extending upwardly from the table. It is apparent the screw J' may be slackened and screw J adjusted to shift the carrier and the knife, after which the screw J is tightened against one of the channel plates, and J' is tightened against the arm of the carrier for fixedly retaining the knife in the required position for cutting a shaving from the surface of the metal stock.

The plates C C' bounding the channel guide are cut away or slotted at c² for the knives D E to act upon the metal stock.

As shown in Figure 2a, the metal stock is flat in cross section with parallel surfaces, and this stock is drawn by the action of the feed and corrugating rolls F through the wipers of the guides f f' and the channel guide c, thus feeding the metal stock with respect to the knives D E. Said knives are positioned for the cutting edges thereof to shave or pare the metal stock as it is fed through the guide c, said knives being retained fixedly in place by the carriers, the

head blocks and the screws. The knives are set to cut away the metal in directions inclined to the faces of the stock, the effect being to cut bevels a' a'' on the faces of the stock, as shown in Figure 2^b, which bevels are reversed to each other and converge so as to result in a sharpened edge a^3 at the penetrating or driving edge of the resulting fastener.

19 It will be noted that the metal stock is shaved by the knives to produce the reversed bevels and the sharpened edge thereon while the stock is in a flat condition, and prior to the operation of the corrugating rolls F upon said stock, said rolls operating to produce transverse crimps in the metal so as to convert the flat metal stock into a length of corrugated metal.

20 The metal stock sharpened on one edge by the shaving or paring process and crimped by the action of the corrugating rolls is used for the production of plain edge corrugated fasteners K of the form shown in Figure 9, it only being necessary to cut the metal into pieces of suitable length after performing the shaving operation and the corrugating operation thereon, suitable means being provided for cutting the shaved and corrugated stock transversely and at proper intervals.

25 The metal stock with its edge shaved and corrugated may, however, be further manipulated to produce on the shaved edge thereof a desired saw tooth formation so as to result in the production of saw tooth corrugated fasteners L shown in Figure 10. To this end, the metal stock is conducted from the corrugating rolls F of Figure 1 to the swaging die M of Figures 1 and 6 and to the cutting dies N O of Figures 1, 7 and 8. After passing the corrugating rolls F the corrugated metal with the shaved edge is fed by a roll P within a channel q of the table Q, and said stock passes first beneath the swaging die M of Figure 6, the operation of which is to swage the corrugated metal below the sharpened edge a^3 so as to produce the bevels m n for the saw teeth to be subsequently produced by the dies N O. As the metal stock passes, with an intermittent feed motion, to the dies N O, said stock is first inclined in one direction and then in an opposite direction, as shown in Figures 7 and 8. The dies N O are each formed with a corrugated face, and said dies act upon the swaged metal m n of the stock in a manner to cut out the metal and produce on the edge of the corrugated stock certain saw teeth with bevels in the convex faces of the corrugations so as to result ultimately in a saw tooth formation with a continuous, or substantially continuous, cutting edge. In addition to cutting out the metal for the formation of saw teeth, the dies (both swaging and cutting) so act

upon the metal at the driving edge as to position the points of the saw teeth in the plane of the medial line of the corrugated metal; thus producing fasteners which drive without deflection into the wood, either with 70 the grain or across the grain of the material.

The means herein shown and described as dies M, N, O, for producing the saw tooth formation upon the driving edge of the corrugated metal stock are analogous to the mechanism for the purpose disclosed in United States Patent No. 1,210,416 granted January 2, 1917, to Cary and Brand, to which reference is made for more detailed 75 disclosure of the construction and operation of said dies and the mechanism or mechanism associated therewith.

25 The shaved metal stock after leaving the cutting mechanism shown in Figures 2 to 85 5 inclusive may be subjected to the action of co-operating die rollers disclosed in my co-pending application Serial No. 475,148, filed June 4, 1921, said die rollers being operable upon the beveled edge flat stock to impart thereto the divergent corrugations s s' with the flat intermediate web t shown in Figure 11, subsequent to which the corrugated sections of the metal are acted on by swaging and cutting dies similar to dies M, N, O, 90 and so organized that said dies swage and cut out the corrugated metal as to result in the saw teeth t' on the driving edge, it being apparent that the continuous length of the prepared metal stock is cut transversely at proper intervals for the production of the individual divergent fasteners S 95 shown in Figure 11.

Having thus fully described the invention, what I claim as new and desire to secure by Letters Patent is:

1. In a machine of the class described, means for directing metal stock in a definite path, a plurality of rockable knife carriers positioned at the respective sides of the path of feed of said metal stock, a plurality of knife blocks, one for each carrier, a plurality of stationary knives, one for each knife block, said knives being positioned in oppositely inclined relation to the path of feed and at the respective sides thereof, and means for separately adjusting the knife blocks and the knives in paths parallel to the faces of the metal stock, whereby the knives are adapted for operation upon the face portions of metal stock adapted to be fed within the stock directing means.

2. In a machine of the class described, means for directing metal stock in a definite path, a plurality of knife carriers positioned at the respective sides of the path of stock feed, a plurality of knife-blocks mounted in said knife carriers for slidable movement with respect thereto, one knife block to each knife carrier, a plurality of sta-

tionary knives, one for each knife block, said stationary knives being positioned at the respective sides of the path of stock feed and inclined thereto, and means for raising and lowering the knife blocks and the stationary knives in paths parallel to the plane of the stock guide.

3. In a machine of the class described, a guide channel, means for feeding metal stock within said guide channel, a plurality of knife carriers positioned at opposite sides of the guide channel, a head block mounted in each knife carrier, a knife in each head block, and means for shifting the head block with respect to the carrier.

4. In a machine of the class described, a guide channel, means for feeding metal stock within said guide channel, a plurality of knife carriers positioned at the respective sides of the guide channel and mounted for pivotal movement, means for fixedly retaining said knife carrier in position relatively to the guide channel, and a shaving knife supported in each knife carrier for adjustment therewith.

5. In a machine of the class described, a guide channel, means for feeding metal stock within said guide channel, a plurality of knife carriers positioned at opposite sides of

the guide channel, a head block mounted in each knife carrier, a knife in each head block, means for retaining the knife in adjusted position relatively to the head block, and means for adjusting the knife carrier with relation to the guide channel.

6. In a machine of the class described, means for feeding metal stock in a definite path, cutting mechanism for shaving said stock on its respective faces and producing a sharpened edge thereon, means for corrugating the metal stock subsequently to the shaving thereof, and means in active relation to the sharpened edge of the corrugated stock for cutting the said edge to produce a saw tooth formation thereon.

7. In a machine of the class described, a guide channel, means for feeding metal stock therein, a plurality of knife carriers positioned adjacent the guide channel, a plurality of head blocks, one for each knife carrier, a knife mounted in each head block, and means whereby the knife is adapted to be raised and lowered relatively to the guide channel.

In testimony whereof I have hereto signed my name this 28th day of September, 1921.

VINCENT RAGONA.
